HYDROMASSAGE TUB

Roy A. Jacuzzi, 3793 Via Granada, Moraga, Calif.
94556, and Peter L. Kosta, 1035 Upper Happy Valley
Road, Lafayette, Calif. 94549

Filed Nov. 28, 1973, Ser. No. 419,814

Term of patent 14 years

Int. Cl. D23—02

U.S. Cl. D23—55

FIG. 1

FIG. 5

FIG. 2

FIG. 3

FIG. 6

FIG. 4

FIG. 1 is a perspective view of a hydromassage tub showing our new design;

FIG. 2 is a top plan view thereof;

FIG. 3 is an end view taken from the left of FIG. 2;

FIG. 4 is an end view taken from the right of FIG. 2;

FIG. 5 is a front elevation view thereof, the rear being a mirror image of the front shown; and

FIG. 6 is a cross-sectional view taken along line 6-6 on FIG. 2.

We claim:

The ornamental design for a hydromassage tub, as illustrated.
